(57) **CLAIM**

What is claimed is the ornamental design for a bottle opener, as shown and described.

DESCRIPTION

FIG. 1 is a top perspective view of a bottle opener showing our new design.

FIG. 2 is a bottom perspective view of the bottle opener of FIG. 1.

FIG. 3 is a front elevational view of the bottle opener of FIG. 1, the back, right side, and left side being a mirror image thereof; and,

FIG. 4 is a top plan view of the bottle opener of FIG. 1, the bottom being a mirror image thereof.
